UNITED STATES PATENT OFFICE

145,886

DESIGN FOR A CIGARETTE LIGHTER

Cecil M. Fox, Toledo, Ohio, assignor to Milton M. Mendelsohn, Chicago, Ill.

Application November 7, 1945, Serial No. 123,526

Term of patent 3½ years

(Cl. D48—27)

To all whom it may concern:

Be it known that I, Cecil M. Fox, a citizen of the United States and resident of Toledo, in the county of Lucas and State of Ohio, have invented a new, original, and ornamental Design for a Cigarette Lighter, of which the following is a specification, reference being had to the accompanying drawing, forming a part thereof.

In the drawing, Fig. 1 is a perspective view of a cigarette lighter showing my new design; Figs.

2, 3 and 4 are top, side and front edge views thereof, respectively; Fig. 5 is a side view different from that shown in Fig. 3, and Figs. 6 and 7 are rear and bottom end views thereof, respectively.

I claim:

The ornamental design for a cigarette lighter, substantially as shown.

CECIL M. FOX.
